(57) CLAIM

The ornamental design for a sole-tape for a golf club head, as shown and described.

DESCRIPTION

FIG. 1 is a front view of a sole-tape for a golf club head. FIG. 2 is a right side view of the sole-tape.

FIG. 3 is a top view of the sole-tape; and,

FIG. 4 is a rear view of the sole-tape.
